BELT SANDER

Frank G. Eskuchen, Chicago, Ill.

Application July 23, 1952, Serial No. 300,545

6 Claims. (Cl. 51—135)

1

This invention relates to a combination tool of the type commonly employed in home workshops. More specifically, the invention relates to a device incorporating in a single unit a bench saw and a belt sander, thus offering to the user a combination of two tools which are in common demand for home workshop use.

The combination tool of the present invention is convenient and simple to operate, and yet extremely inexpensive to construct. By the present invention, a single table structure is employed for both the saw and the sander. The sander is, by a single operation, removed from the surface of the saw table, thus leaving the table unobstructed for convenience of use of the saw, and simultaneously uncoupled from its motive means, thus eliminating the hazard and inconvenience which would arise from permitting the sander to continue to operate while not in use.

For understanding of the invention, reference is made to the attached drawing, in which:

Fig. 1 is a front elevation of the combination bench saw and belt sander of the invention, with a portion of the housing thereof broken away in section to show the interior thereof;

Fig. 2 is a fragmentary front elevation of the housing which constitutes a portion of the device of Fig. 1;

Fig. 3 is a top plan view of the device of Fig. 1, a portion being in broken section;

Fig. 4 is an end elevation of the device of Fig. 1;

Fig. 5 is a fragmentary vertical section taken along the line 5—5 of Fig. 3 in the direction indicated by arrows;

Fig. 6 is a detail view, partially in section, taken along the line 6—6 of Fig. 4;

Fig. 7 is a fragmentary vertical sectional view taken along the line 7—7 of Fig. 5;

Fig. 8 is an offset sectional view taken along the line 8—8 of Fig. 4;

Fig. 9 is a vertical sectional view taken along the line 9—9 of Fig. 8;

Fig. 10 is a detail sectional view illustrating the sander carriage which constitutes a portion of the invention in the lowered or withdrawn position.

The saw portion of the device of the invention generally resembles a conventional bench or table saw of the type which is now in common use. The open-top housing 20, which may be secured by bolts 22 to a bench or table-top 24, has pivoted on the upper end thereof a broad flat table 28. Depending from and integral with the table 28 are brackets 30 which abut against the outer end surfaces of the housing 20. Pivotal mounting of

2

the table 28 is accomplished by bolts 31 which extend through apertures in the brackets 30 and are threaded into nuts 33, which are welded to the housing 20. The brackets 30 are provided with arcuate slots 32, through which extend studs 34, which extend through apertures 35 in the housing 20. The studs 34 are provided with wing-nuts 38. Tightening of the wing-nuts 38 secures the table 28 in horizontal or tilting relation to the housing 20, the ears or flaps 30 having calibration markings to indicate the angle of tilt. Pivoted inside the housing 20 by means of bolts 39 is a carriage or cradle 41. Affixed to each side of the cradle 41 is a stud 40, which extends outward through an arcuate slot 42 in the side of the housing 20. Journalled in suitable bearings in upwardly extending oppositely disposed arms 44 of the cradle 41 is a shaft 46, upon which is mounted a circular saw blade 48. The saw blade extends upwardly through a slot 50 in the table 28. The extent of protrusion of the saw blade 48 above the surface of the table 28 is thus adjustable by pivoting of the cradle 41. The cradle 41 is locked at any desired position by tightening of knobs 52 upon studs 40. The shaft 46 is provided with a pulley 54, which may be coupled by a suitable belt to a motor placed beneath the bench or table-top 24.

It will be recognized that the structure thus far described is, as stated above, generally similar to a conventional bench or table saw of the type commonly known as a "tilt table" saw. There are also provided, as is conventional in saws of this type, a blade guard 60, mounted by a bracket 61, a movable rip fence 62, and a mitre gauge or protractor assembly, generally designated by the numeral 64. The position of the rip fence 62 may be adjusted with respect to the blade 48 by sliding the fence 62 along the table 28, fastening into position being accomplished by means of a knob 66 and thumbscrew 67. The mitre gauge assembly slides back and forth in a milled groove 68 in the upper surface of the table 28, the protractor and work stop portion 70 of this assembly being pivoted at 72 on the slide bar 74, and being locked in angular position by a knob 76.

In accordance with the present invention, there is provided in the combination device thereof a novel belt sander assembly which is located near one side of the table 28 in a position remote from the saw blade 48. A rectangular opening 80 in the table 28 has depending from the sides thereof brackets 82, which are formed integrally with the table 28 and depend downwardly therefrom. The brackets 82 each have a pair of slots 84 which ex-

tend downwardly and frontwardly. Mounted between these brackets 82 is a belt sander assembly generally designated by the numeral 90. The carriage 92 of this assembly is a channel shaped member having a flat upper portion 94, which serves as a backing plate, and depending side portions 96. At the ends of this assembly are journalled front and back drums 98 and 100. The rear drum 100 is affixed to a shaft 102 by a screw 104, which is threaded transversely through the shaft 102 (see Fig. 10), the surface of the drum 100 being countersunk to receive the head of the screw 104. The drum 100 and the shaft 102 are thus rigidly coupled together. An impregnated powdered metal sleeve bearing 106 is press-fitted through each of the sides 96 of the carriage 92, and the shaft 102 is journalled in these bearings. The extending end of the shaft 102 is provided with a pulley 110. The front drum 98 has press-fitted through the ends thereof sleeve bearings 112 similar to the bearings 106. Through these bearings extends a shaft 114, the ends of which extend at either side of the carriage through elongated slots 116 formed in the side members 96 of the carriage. At the rear ends of these slots 116 are laterally extending ears 118, which are formed integrally with the side members by a stamping and bending operation which simultaneously produces the slots 116 and the ears 118. The ears 118 have threaded apertures 120. Thumbscrews 122 extend forwardly through the ears 118. The shaft 114 is partially bored radially at 126 at each end to freely receive the ends of the thumbscrews 122. It will thus be seen that the sanding belt 130, which is mounted on the drums, will be driven by the shaft 102, to which the drum 100 is rigidly coupled, and the sanding belt will thus drive the front drum 98. The tension on the belt 130 may be adjusted by loosening or tightening of the thumbscrews 122. It will be noted that the front shaft 114 does not rotate, the seating of the ends of the screws 122 in the bores 126 serving to maintain the rotative position of the shaft 114. The slotting 116 of the side members 96 permits the above described variation of the position of the shaft 114 to permit adjustment of the belt tension. In order to prevent loosening of the thumbscrews 122 due to vibration of the machine, there are provided compression springs 134, which bear against the ears 118 and washers 136, which latter are provided beneath the heads of the screws 122.

The side portions 96 of the sander carriage 92 are provided with threaded apertures 140, which are in register with the slots 84 in the brackets 82 described above. Thumbscrews 142 extend through the slots 84 and are threaded into the apertures 140 in the carriage 92. Tightening of the thumbscrews 142, aided by washers 144 inserted under the heads thereof, serves to lock the sander carriage 92 into position relative to the sander table 28. Upon loosening of the thumbscrews 142, the carriage 92 may be slidingly moved to any place within the limits defined by the slots 84. When the screws 142 are at their uppermost (and rearwardmost) position in the slots 84, the top surface 94 of the carriage 92 is flush with the top of the table 28, as shown in Fig. 7. When the screws 142 are at their lowermost (and forwardmost) position, the top 94 of the carriage 92 is substantially below the level of the table 28, as shown in Fig. 10.

In the illustrated embodiment, the pulley 110, which is rearward and upward of the saw shaft 46, is coupled to a pulley 112 provided for this purpose on the end of the shaft 46 by a belt 114.

If desired, however, this coupling may obviously be omitted and the shaft 102 may be independently driven.

At the front edge of the rectangular opening 80 in the table 28 through which the upper surface of the sander may be elevated or lowered as described above, there is provided an L-shaped work stop 150, which is secured to the table 28 by screws 152. When the saw portion of the combination tool is in use with work pieces of a size sufficient to require unobstructed use of the table 28, the work stop 150 may easily be removed by removal of the screws 152.

To further add to the utility of the combination home work shop tool of the invention, to the outer end of the shaft 46 is secured an auxiliary shaft 160, to which is removably secured a drill chuck 162, which extends beyond the end of the table 28. The shaft 160 and chuck 162 are provided with socket bores 161 and 163 to permit ready removal of the chuck by the employment of rod wrenches to permit use of the shaft for other auxiliary purposes.

The operation and advantageous features of the combination tool herein described will readily be understood by those skilled in the art. Because the lowering of the carriage 92 beneath the surface of the table 28 at the same time moves the shaft 102, which is the drive shaft for the belt sander, downwardly and forwardly toward the main shaft 46, the operation of lowering the sander carriage simultaneously removes the belt tension of the belt 114, thus removing the drive from the sander. Because of this arrangement, the sander is automatically engaged in the drive system when it is in the operating or elevated position, and is automatically inactivated when it is in the lowered position wherein it is placed when the saw portion of the device is being used. Where an independent drive for the sander assembly is employed, as discussed above, it may also be suitably placed so as to produce such automatic engagement and disengagement of the sander.

As is well known, sanding belts will with extended use stretch to some extent, and differential stretching of the various portions of the belt may occur. With the present structure, adjustment for such differential stretching may readily be made by varying the adjustment of the thumbscrews 122 at the opposite sides of the belt, thus maintaining the tension on the two sides of the belt equal and preventing any tendency for the belt to run to either side of the drums.

Replacement of the sanding belt is likewise a simple operation, requiring merely the removal of thumbscrews 142, whereupon the entire sander assembly drops out from between the brackets 82, and the old belt may thus be removed and a new belt installed with proper adjustment of tension.

It will also be seen that the present structure, in addition to presenting the convenience features described above, affords a construction which is extremely inexpensive.

It will be understood that various features of the device described and illustrated in the drawing will readily be adapted by persons skilled in the art to combination tools which differ substantially in appearance and in detail from that herein illustrated. Accordingly, the scope of the invention shall not be deemed to be limited by the particular embodiment selected for purposes of illustration, but shall be defined only by the appended claims.

What is claimed is:

1. A belt sander assembly for a combination

workshop tool comprising a work table, a drive shaft journalled beneath the work table, the work table having a substantially rectangular opening, opposed brackets depending from the sides of said opening, a sander carriage between said brackets including a flat upper backing plate and depending side members, rotatable drums at opposite ends of the carriage extending between the side members, each bracket having a pair of angularly sloping slots, clamping means extending through the slots and slideable therein and fixedly positioned on the carriage, the side members of the carriage being longitudinally slotted at one end thereof, a shaft extending through said slots and reciprocable therein, one of the drums being mounted on said shaft, a pair of ears extending laterally from the side members adjacent to the slots and screws respectively threaded through said ears, the shaft having radial recesses in which the ends of the screws are seated, a third shaft upon which the other of said drums is rigidly mounted, said third shaft being parallel with said drive shaft and being further from the drive shaft when the carriage is clamped in the upper sliding position in said angular slots than when the carriage is clamped in the lower sliding position.

2. A belt sander assembly for a combination workshop tool comprising a table member having a substantially rectangular opening therethrough, opposed brackets depending from the sides of said opening, a sander carriage between said brackets including a flat upper plate and depending side members, rotatable drums at opposite ends of the carriage extending between the side members, each bracket having a pair of angularly sloping slots, and clamping means extending through said slots and slideable therein and fixedly positioned on the carriage, whereby the carriage may be mounted flush with the table member or withdrawn beneath the table member.

3. The apparatus of claim 2 wherein the side members of the sander carriage are longitudinally slotted at one end thereof and there are provided a shaft extending through said slots and

reciprocable therein, one of the drums being mounted on said shaft, and means for longitudinally positioning said shaft in the slots, whereby the spacing of said drums may be varied to vary the tension upon a sander belt.

5. The apparatus of claim 3 wherein the means for longitudinally positioning the shaft in the slots comprises a pair of ears extending laterally from the side members adjacent to the slots and screws respectively threaded through said ears, the shaft having radial recesses in which the ends of the screws are seated.

10. A belt sander assembly for a combination workshop tool comprising a work table, a sander carriage including a flat back ing plate and rotatable drums at opposite ends of the carriage adapted to drive a sander belt over the backing plate, mutually slideable means on the carriage and on the table for selectively mounting the carriage in a position wherein the upper plate of the carriage is in the plane of the table and in a position wherein the upper plate of the carriage is in a plane beneath the plane of the table, and means responsive to raising and lowering of the table respectively to activate and inactivate said drums.

15. A belt sander assembly for a combination workshop tool comprising a work table, a sander carriage including a flat back ing plate and rotatable drums at opposite ends of the carriage adapted to drive a sander belt over the backing plate, mutually slideable means on the carriage and on the table for selectively mounting the carriage in a position wherein the upper plate of the carriage is in the plane of the table and in a position wherein the upper plate of the carriage is in a plane beneath the plane of the table, and means responsive to raising and lowering of the table respectively to activate and inactivate said drums.

20. A belt sander assembly for a combination workshop tool comprising a work table, a sander carriage including a flat back ing plate and rotatable drums at opposite ends of the carriage adapted to drive a sander belt over the backing plate, mutually slideable means on the carriage and on the table for selectively mounting the carriage in a position wherein the upper plate of the carriage is in the plane of the table and in a position wherein the upper plate of the carriage is in a plane beneath the plane of the table, and means responsive to raising and lowering of the table respectively to activate and inactivate said drums.

25. A belt sander assembly for a combination workshop tool comprising a work table, a sander carriage including a flat back ing plate and rotatable drums at opposite ends of the carriage adapted to drive a sander belt over the backing plate, mutually slideable means on the carriage and on the table for selectively mounting the carriage in a position wherein the upper plate of the carriage is in the plane of the table and in a position wherein the upper plate of the carriage is in a plane beneath the plane of the table, and means responsive to raising and lowering of the table respectively to activate and inactivate said drums.

30. A belt sander assembly for a combination workshop tool comprising a work table, a sander carriage including a flat back ing plate and rotatable drums at opposite ends of the carriage adapted to drive a sander belt over the backing plate, mutually slideable means on the carriage and on the table for selectively mounting the carriage in a position wherein the upper plate of the carriage is in the plane of the table and in a position wherein the upper plate of the carriage is in a plane beneath the plane of the table, and means responsive to raising and lowering of the table respectively to activate and inactivate said drums.

35. A belt sander assembly for a combination workshop tool comprising a work table, a sander carriage including a flat back ing plate and rotatable drums at opposite ends of the carriage adapted to drive a sander belt over the backing plate, mutually slideable means on the carriage and on the table for selectively mounting the carriage in a position wherein the upper plate of the carriage is in the plane of the table and in a position wherein the upper plate of the carriage is in a plane beneath the plane of the table, and means responsive to raising and lowering of the table respectively to activate and inactivate said drums.
